Primary Examiner — Sheryl Lane*Assistant Examiner* — Catherine Posthauer(74) *Attorney, Agent, or Firm* — Chun-Ming Shih; HDLS IPR Services(57) **CLAIM**

The ornamental design for an inner packing element of box, as shown and described.

DESCRIPTION

FIG. 1 is a perspective view of an inner packing element of box showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is second perspective view showing the inner packing element of box; and,

FIG. 9 is a perspective view showing the inner packing element of box in use.

The broken lines shown in FIG. 9 represent environmental subject matter and form no part of the claimed design.
